US00D684067S

(12) **United States Design Patent**
Nielsen et al.

(10) **Patent No.:** US D684,067 S
(45) **Date of Patent:** ** Jun. 11, 2013

(54) **MODULAR MARKING DEVICE**

(75) Inventors: **Steven Nielsen**, North Palm Beach, FL (US); **Curtis Chambers**, Palm Beach Gardens, FL (US); **Jeffrey Farr**, Tequesta, FL (US); **James T. Sener**, Glastonbury, CT (US); **Christopher D. Hageman**, South Glastonbury, CT (US)

(73) Assignee: **Certusview Technologies, LLC**, Palm Beach Gardens, FL (US)

(**) Term: **14 Years**

(21) Appl. No.: **29/413,451**

(22) Filed: **Feb. 15, 2012**

(51) **LOC (9) Cl.** 10-04

(52) **U.S. Cl.**

USPC **D10/47**

(58) **Field of Classification Search**

USPC D10/46, 47, 70; 324/67, 202, 326-329, 324/233, 207.2, 226, 345, 242, 243, 244, 324/253, 225, 228, 252, 248, 301; 340/368, 340/933; 702/38; 172/371, 438; 707/822, 707/E17.005

See application file for complete search history.

CLAIM

The ornamental design for a modular marking device, as shown and described.

DESCRIPTION

FIG. 1 is a rear view of the modular marking device;
FIG. 2 is a left side view thereof;
FIG. 3 is a front side view thereof;
FIG. 4 is a top view thereof;
FIG. 5 is a bottom view thereof;
FIG. 6 is a right side view thereof; and,
FIG. 7 is a perspective view thereof.
